INVENTOR

Thomas A. D'Urbilis,
By Owen & Owen,
His attorney.

UNITED STATES PATENT OFFICE.

THOMAS A. DE VILBISS, OF TOLEDO, OHIO.

AIR-BRUSH.

1,045,266.

Specification of Letters Patent. Patented Nov. 26, 1912.

Application filed October 16, 1911. Serial No. 655,074.

To all whom it may concern:

Be it known that I, THOMAS A. DE VILBISS, a citizen of the United States, and a resident of Toledo, in the county of Lucas and State of Ohio, have invented a certain new and useful Air-Brush; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to air-brushes or atomizers of the type particularly adapted for the applying of lacquer, varnish, paint, bronze or other pigment of a liquid or powdery nature in spray form upon a receiving 20 surface.

The object of my invention is the provision of an improved instrument of this character which is simple, light and durable in its construction, inexpensive of manufacture, and easy to operate.

A further object of my invention is the provision of means which is easily operable to control the simultaneous opening and closing movements of the fluid pressure and pigment valves whereby the actuating fluid and the pigment are always mixed in proper proportions before being discharged from the nozzle.

The invention is fully described in the following specification, and while, in its broader aspect, it is capable of embodiment in numerous forms, a preferred embodiment thereof is illustrated in the accompanying drawings, in which,—

40 Figure 1 is a side elevation of an instrument embodying my invention. Fig. 2 is a top plan view thereof, and Fig. 3 is a central, vertical, longitudinal section of the upper portion thereof with the handle partly broken away.

Referring to the drawings, 1 designates the barrel or spray-head of the instrument, which barrel is of elongated form and provided throughout its length with a bore 2.

50 A nipple 3 projects laterally from the under-side of this barrel, preferably adjacent to the forward end thereof, and is adapted for the attaching of a hose or tube coupling 4 thereto, the tube of which (not shown) leads

to any suitable source of supply of pigment or other substance to be applied in spray form to a receiving surface.

The forward end of the barrel 1 is equipped with the customary concentric nozzles 5 and 6, which are shown in the present instance as being respectively threaded onto and into the barrel end, the former being the air or fluid pressure nozzle and the other the liquid nozzle or that which communicates through the barrel bore with the substance to be sprayed.

An enlargement 7 is provided in the present instance on the top of the forward end portion of the barrel 1 and is bored to form a chamber 8, which is in communication with the chamber 9 between the nozzles 5 and 6 through a passage 10 in the barrel and with a source of fluid pressure through a nipple 11 and flexible hose tube (not shown), the tube and nipple being connected by a coupling 12, or in any other suitable manner. A valve 13 is disposed within the chamber 8 for seating forwardly against a seat 14 therein and has a stem 15 projecting forward therefrom through said seat and the forward end of the chamber. A coiled expansion spring 16 acts between a screw-plug 17, which closes the rear end of the chamber 8, and the valve 13 to normally maintain the latter seated.

A plunger 18 is mounted for reciprocal movements in the rear end portion of the bore 2 of the barrel, and has a pin or stem 19 projecting from its forward end with its free end projecting within the throat of the nozzle 6 and normally closing the restricted discharge orifice thereof. The purpose of the pin or stem 19 is threefold, namely, to serve as a valve to close the discharge orifice of the liquid nozzle when the instrument is not being operated, to clean such orifice of accumulated matter, and to cooperate with the conical form of the nozzle to regulate the quantity of discharge of pigment or other substance therefrom and the consequent spray density, as will hereinafter be more fully described.

A cap or cylinder 20 is threaded or otherwise suitably attached to the rear end of the barrel 1 and has its bore preferably slightly larger than the barrel bore and forming an extension thereof for the rear end of the plunger 18 to work in. A coiled expansion

spring 21 is mounted within the cap 20 and acts on the rear end of the plunger to normally hold the plunger at the limit of its forward movement, which movement is limited by a shoulder 22 on the plunger coacting with the rear barrel end, as is apparent. An adjustable stop screw 23 is threaded through the rear end of the cap 20 and coacts with a stem 24 projecting from the rear 10 end of the plunger 18 within the spring 21 to limit the opening or rearward movements of the plunger, as desired.

A handle 25 projects downward from the barrel 1 adjacent to the rear end thereof, 15 and is shown, in the present instance, as having its upper end forming the finger 26, which extends upward and forward therefrom over the barrel. This finger may, however, be formed in any other suitable 20 manner.

A control lever 27 has its upper end portion forked and straddling the barrel 1 in advance of the handle 25 with the free or upper ends of its furcations pivoted to the 25 free-end portion of the finger 26, as at 28, and has its lower end extended a short distance below the barrel and preferably fashioned in the form of a trigger to facilitate an engaging and rearward moving of the 30 same by the first finger of a hand grasping the handle.

A bar 29 is pivoted at its rear end to one side of the lever 27 adjacent to its pivot, as at 30, and projects forward therefrom at one 35 side of the enlargement 7, with its forward end terminating in advance thereof and bent laterally in abutment with the outer end of the air valve stem 15. The bar 29 is shown as provided at its bent end with a socket 31 40 in which the outer stem end seats, and is adapted to communicate an unseating movement to the valve 13 from a rearward oscillation of the lever 27 from normal position. A movement of the lever 27 from normal 45 position also imparts an opening or rearward retracting movement to the plunger 18 through the medium of the connecting bars 32, 32. These bars are pivoted at their forward ends to the lever 27 below the point of 50 attachment of the bar 29 thereto, and are shown as having their rear ends connected over the barrel 1 by a yoke 33 and in notched thrust engagement with studs 34 projecting laterally from opposite sides of the plunger 55 18 through registering slots 35 in the rear end portion of the barrel.

It is apparent with this construction that a rearward movement of the control-lever 27 will impart simultaneous opening movements to the fluid pressure valve 13 and the plunger 18, and that the relative points of attaching of the bars 29 and 32 to the lever causes the plunger to have greater movements than the fluid valve. I wish it understood, however, that while it is preferable 65

to the practical operation of a device of this character it is not necessary to connect the operable parts in the manner described.

36 designates a spur, which projects forward from the handle 25 adjacent to the lower end of the lever 27 to serve as a guard therefor, and also rests upon the second finger of the hand grasping the handle to support the handle in proper position without tightly gripping it for such purpose. 75

The operation of my improved instrument is as follows: The nipples 3 and 11 being respectively connected to suitable sources of pigment or other substance to be sprayed and air or other suitable fluid pressure, and the stop-screw 23 being set for the desired spray density, the operator grasps the handle 25 in one hand with preferably the first finger of such hand engaging the control lever or trigger 27. He then draws 80 the lever back until stopped by the plunger striking the stop-screw 23, or to a lesser extent as desired, thus imparting proper proportional opening movements to the air-valve 13 and the plunger 18, such movements being against the influence of the springs 16 and 21. Upon an opening of the valve 13 the actuating air or other fluid under pressure rushes into the nozzle chamber 9 and discharges therefrom in a thin 85 stream around the discharge end of the nozzle 6, thus creating a suction or vacuum action within such nozzle to draw the liquid pigment or other substance with which the barrel is connected, into the barrel and outward through the nozzle 6, as is well understood in the art. To clean the liquid nozzle of accumulated matter, the operator merely releases the pressure of his finger upon the lever 27, thus permitting the plunger to 90 move forward for its pin 19 to close and clean the liquid nozzle orifice and the air-valve 13 to close. The spray density can be easily regulated while the instrument is being operated by simply adjusting the 95 stop-screw 23 with the hand which is not grasping the handle.

While my invention is shown and described as used in connection with an apparatus in which material is drawn from a 100 source of supply by the suction action created by the rapid discharge of air past the end of the nozzle 6, it is also adapted for use in the spraying of powdered or granular substances the nature of which would not 105 permit the practical drawing thereof through the nozzle 6, barrel bore 2, etc., by suction, but which must be forced there-through by some suitable means for such purpose, the discharging of the fluid in 110 such case around the discharge end of the nozzle 6 serving only to pick up and carry the substance with it in spray form as it is ejected from the nozzle.

I wish it understood that my invention is 115

not limited to any specific construction or arrangement of the parts except in so far as such limitations are specified in the claims.

Having thus described my invention, what I claim as new and desire to secure by Letters Patent, is:—

1. In an instrument of the class described, a spray head having an elongated bore with liquid and fluid nozzles at one end thereof, a handle projecting laterally from the spray head adjacent to the other end thereof, a plunger mounted for reciprocatory movements in said bore and having a needle projecting therefrom to close the discharge orifice of the liquid nozzle, a liquid inlet nipple projecting laterally from said spray head adjacent the discharge end thereof with its opening in communication with said bore, an enlargement formed on one side of the spray head adjacent its discharge end and forming a valve chamber in communication with the fluid nozzle, a valve yieldingly mounted in said chamber to normally close said communication and having a stem projecting forwardly therefrom without the enlargement, a trigger fulcrumed above the spray head and having its lower end projecting below the spray head in advance of the handle, a link connecting said trigger and plunger to impart opening movements to the plunger when the trigger is moved toward the handle, and a bar attached to said trigger intermediate said link and the trigger fulcrum and projecting forwardly from the trigger with its free end attached to said valve stem to impart opening movements to said stem and its valve when the trigger is pulled.
2. An air brush having an elongated spray head provided with a passage therethrough and having one end provided with concentric liquid and air nozzles, said spray head also having a liquid inlet nipple projecting downwardly therefrom adjacent to its discharge end and having an enlargement on its upper side in opposition to said nipple, said enlargement forming an air-valve chamber, which chamber is in communication with the air nozzle, a valve mounted in said chamber and normally acting to close said communication and having a stem projecting forwardly therefrom without the enlargement, a handle projecting laterally from the spray head adjacent to its rear end, said handle having a part projecting upwardly and forwardly therefrom over a spray head, a plunger mounted in said spray head for controlling the liquid discharge orifice, a trigger pivoted above the spray head to said handle part and projecting below the spray head in advance of the handle, a bar connecting said trigger and plunger to impart opening movements to the plunger when the trigger is pulled to the handle and a bar pivoted to the trigger above said first bar and having its forward end angled in advance of said enlargement and socketed to receive the forward end of said valve stem to impart opening movements thereto when the trigger is pulled.

In testimony whereof, I have hereunto signed my name to this specification in the presence of two subscribing witnesses.

THOMAS A. DE VILBISS.
